UNITED STATES PATENT OFFICE.

CHARLES D. MCCOLLOUGH, OF DES MOINES, IOWA.

DESIGN FOR A TIRE-CORE.

59,024.

Specification for Design. Patented Sept. 13, 1921.

Application filed April 3, 1920. Serial No. 371,169. Term of patent 14 years.

To all whom it may concern:

Be it known that I, CHARLES D. MCCOLLOUGH, a citizen of the United States of America, and resident of Des Moines, in the county of Polk and State of Iowa, have invented a new original, and ornamental Design for Tire-Cores, of which the following is a specification, reference being had to the accompanying drawing, forming part thereof.

Figures 1 and 2 are opposite side elevations of a segment of a tire core, showing my new design. Figs. 3, 4 and 5 are cross-sections on the respective lines 3—3, 4—4 and 5—5 of Fig. 2.

I claim:

The ornamental design for a tire core, as shown.

CHARLES D. MCCOLLOUGH.
